US0D1007816S

(12) United States Design Patent (10) Patent No.: US D1,007,816 S
(45) Date of Patent: * Dec. 19, 2023

(54) SHORTS

(71) Applicant: ORIENTAL-JADE HK CO., LIMITED, Shanghai (CN)

(72) Inventor: Kwok Kit Edwin Lau, Shanghai (CN)

(73) Assignee: ORIENTAL-JADE HK CO., LIMITED, Shanghai (CN)

() Term: 15 Years

(21) Appl. No.: 29/799,749

(22) Filed: Jul. 16, 2021

(51) LOC (14) Cl. 02-02

(52) U.S. Cl.

USPC D2/731

(57) CLAIM

The ornamental design for shorts, as shown and described.

DESCRIPTION

FIG. 1 is a perspective view of shorts showing my new design;

FIG. 2 is a top view thereof;

FIG. 3 is a bottom view thereof;

FIG. 4 is a rear view thereof;

FIG. 5 is a front view thereof;

FIG. 6 is a right side view thereof; and,

FIG. 7 is a left side view thereof.

The broken lines define the bounds of the claim and form no part of the claimed design.

1 Claim, 7 Drawing Sheets
